UNITED STATES PATENT OFFICE.

EDMUND KIKUT, OF CHARLOTTENBURG, GERMANY.

MEANS FOR UTILIZING WORKING POWER OF COMPRESSED INFLAMMABLE GAS.

SPECIFICATION forming part of Letters Patent No. 687,242, dated November 26, 1901.

Application filed January 28, 1901, Serial No. 45,183. (No model.)

To all whom it may concern:

Be it known that I, EDMUND KIKUT, a subject of the King of Prussia, German Emperor, and a resident No. 6 Stuttgarter Platz, Charlottenburg, near Berlin, in the Kingdom of Prussia, German Empire, have invented certain new and useful Means for Utilizing the Working Power of Compressed Inflammable Gas, of which the following is a specification.

10 This invention relates to means for utilizing the working power of compressed inflammable gas or gases; and my invention consists in general in utilizing the compressed inflammable gas or gas mixture in a jet-blown apparatus or in the jet-nozzle proper of the same, and in particular in employing the jet-blown apparatus or the jet-nozzle proper, in which the compressed inflammable gas is made use of for driving a turbine engine by either the mixture of the combustion-gases and air produced by the jet-blown apparatus or solely by the air sucked in by said apparatus and driven through the same by the action of the jet of the compressed inflammable gas. Owing to this means the turbine engine, or, more particularly, the turbine wheel of said engine, is subjected either but to a comparatively low temperature or heat or to no heat at all, which is the case 25 if the turbine wheel is actuated by the air sucked in by the jet-blown apparatus.

20 In order to make my invention more clear, I refer to the accompanying drawing, in which is represented a vertical longitudinal section 30 through one form of construction of apparatus constructed according to my invention.

The jet-nozzle proper, *a*, of a jet-blown apparatus is connected by the pipe *b* with a generator *c*, adapted to produce an inflammable gas—for instance, Dawson gas—which is generated by leading a mixture of steam and air to and into the burning coal contained in the lower part of the generator *c*. In the form of construction shown the burning coal is employed also for producing the steam necessary for generating the inflammable gas. The generator *c* is surrounded by a vessel *d*, forming the boiler, and the steam produced in this boiler is led by a pipe *e* to 45 an auxiliary jet-blown apparatus *f*, driving air into a pipe *g*, so that a mixture of steam and air is produced in this pipe. The pipe *g*

projects upward from a chamber *r*, connected with another chamber *s* by a number of pipes *t*. These pipes are heated by means of the 55 hot gases issuing forth from the jet-blown apparatus, as will more fully be described hereinafter, and the hot mixture of steam and air entering into and collecting within the chamber *s* passes over into a pipe *g'*, from 60 the end of which a part of said mixture passes through a branch pipe *h* into the generator *c*, in which said part of the mixture comes in contact with the burning coal, so that Dawson gas is produced. This gas passes through 65 the pipe *b* to the jet-nozzle proper *a*, and, also the other part of the mixture of steam and air flowing through the pipe *g'* is driven to and into the nozzle *a* through the pipe *i*, which connects said nozzle with the pipe *g'*. The inflammable 70 gas coming from the pipe *b* and the mixture of steam and air coming from the pipe *i* get mixed within the nozzle *a*, and the inflammable mixture thus produced is ignited by means of a piece of palladium-wire *k*, located within 75 the nozzle *a*. There arises thus a powerful flame issuing forth from the nozzle *a* into and through the air-nozzle *l*, forming part of the jet-blown apparatus. The burning gas mixes with the air sucked in by the nozzle *l*, 80 and this mixture is then led through another nozzle *m*, forming also a part of the jet-blown apparatus. The hot gases issuing forth from the whole jet-blown apparatus pass into a channel *v*, which is crossed by the pipes 85 *t* aforementioned, and these pipes are thus powerfully heated by said gases, so that also the mixture of steam and air flowing from the chamber *r* through the pipes *t* to the chamber *s* is very strongly heated, and owing to all this 90 the calorific power of the inflammable gas is utilized in a very high degree. The products of combustion leave the channel *v* at *w*.

The air-nozzles *l* and *m* and the end part of the gas-nozzle *k* are inclosed in a casing *x*, the 95 upper part of which forms a turbine engine and contains, therefore, a turbine wheel *y*. The front wall of the casing *x* is provided with guide-blades *z*, directing the air against and into the blades of the turbine, so that this 100 wheel is kept in rotation as long as air is sucked into the casing *x* by the action of the jet-blown apparatus *a l m*.

The heat produced in this apparatus is

nearly completely prevented from injuriously affecting the turbine engine or the turbine wheel, respectively, as this is exposed only to the action of the cold air streaming into the 5 casing α from the outer atmosphere. I wish it to be understood, however, that I do not limit myself to exactly this form of construction, as I may well drive the jet produced in the jet-blowing apparatus into a casing similar to α , the arrangement being then such that the turbine wheel is operated not by the outer air, but by the jet of combustion gases and air streaming forth from the jet-blowing apparatus.

15 Having thus fully described the nature of my invention, what I desire to secure by Letters Patent of the United States is—

1. The combination with the jet - nozzle proper of a jet-blowing apparatus, of a generator adapted to produce an inflammable gas, a pipe connecting the gas-space of said generator with said nozzle so as to feed the latter with said gas and cause this latter to form the jet necessary for driving the jet-blowing apparatus, another pipe connecting the said nozzle with the outer air, a third pipe connecting said other pipe with the fuel-space of the said generator, and an auxiliary jet-blower adapted to be actuated by steam and arranged so as to force air into the last-mentioned two pipes, as set forth.

2. The combination with the jet - nozzle proper of a jet-blowing apparatus, of a generator adapted to produce an inflammable gas or gas mixture, a pipe connecting the gas-space of said generator with said nozzle, another pipe connecting the said nozzle with the outer air, a third pipe connecting said other pipe with the fuel-space of the said generator, 40 a boiler so arranged as to be adapted to be heated by the burning fuel in said fuel-space, an auxiliary jet-blower arranged so as to force air into the last-mentioned two pipes, and a connection between said auxiliary jet-blower 45 and the steam-space of said boiler, as set forth.

3. The combination with the jet - nozzle proper of a jet-blowing apparatus, of a generator adapted to produce an inflammable gas or gas mixture, a pipe connecting the gas-space of said generator with said nozzle, a 50 boiler so arranged as to be adapted to be

heated by the burning fuel in said fuel-space, a jacket around the said nozzle, an air-nozzle forming part of the jet-blowing apparatus, a jacket around said air-nozzle, and connections between said jackets and the water-space as well as the steam-space of the said boiler, as set forth.

4. The combination with the jet - nozzle proper of a jet-blowing apparatus, of a generator adapted to produce an inflammable gas, a pipe connecting the gas-space of said generator with said nozzle, another pipe connecting the said nozzle with a closed chamber, pipes connecting this chamber with another closed chamber, an auxiliary jet-blowing apparatus adapted to be actuated by steam and arranged so as to force air into the last-mentioned chamber, a boiler so arranged as to be adapted to be heated by the burning fuel in the generator, and a connection between the steam-space of this boiler and said auxiliary jet-blower, as set forth.

5. The combination with the jet - nozzle proper of a jet-blowing apparatus, of a generator adapted to produce an inflammable gas or gas mixture, a pipe connecting the gas-space of said generator with said nozzle, another pipe connecting the said nozzle with a closed chamber, pipes connecting this chamber with another closed chamber, an auxiliary jet-blowing apparatus adapted to be actuated by steam and arranged so as to force air into the last-named chamber, air-nozzles forming parts of the first-mentioned jet-blowing apparatus, a casing around the pipes which connect the two chambers, another casing surrounding the said nozzles, a connection between said two casings, a turbine wheel located in the second casing, and guide-blades 90 fixed to said second casing and located opposite to the blades of the turbine wheel so as to actuate the latter by means of the air drawn into the said casing under the action of the first-mentioned jet-blowing apparatus, as set forth.

In witness whereof I have hereunto set my hand in presence of two witnesses.

EDMUND KIKUT.
